UNITED STATES PATENT OFFICE.

NATHAN J. GOODMAN, OF ST. LOUIS, MISSOURI, ASSIGNOR TO MODERN SPECIALTIES MFG. CO., OF WILMINGTON, DELAWARE, A CORPORATION OF DELAWARE.

APPAREL-COLLAR.

1,294,085.

Specification of Letters Patent. Patented Feb. 11, 1919.

Application filed June 22, 1917. Serial No. 178,441.

To all whom it may concern:

Be it known that I, NATHAN J. GOODMAN, a citizen of the United States, residing at the city of St. Louis and State of Missouri, have invented new and useful Apparel-Collars, of which the following is a specification.

My invention relates to improvements in apparel collars, wherein tie holding loops secured to the collar band operate in conjunction with the tie to hold the collar top, that is its outermost or exposed part, in a smooth, flat and upright position about the wearer's neck and the tie with its "knot" in a position next the folding line or uppermost margin of the collar.

My object is to provide a collar of the "soft," "turnover" or "negligée" variety, of inexpensive construction, having loops secured to the inside face of the collar band adjacent its ends, through which a tie may be threaded and which loops are provided with flexible elements arranged to be detachably securable to the collar band and which, when "loosed" or unsecured facilitate the threading of the tie and when secured serve to hold the tie elevated to the folding line of the collar, which features of construction serve to hold the tie including its "knot" to the uppermost margin of the collar, that is to the folding line, so that the tie will hold the collar properly "set" and its top or exposed portion in a smooth, flat and upright position about the wearer's neck.

My invention consists in the construction, arrangement and combination of parts which will be fully, clearly and concisely set forth in my specification, pointed out in my claims and illustrated by the accompanying drawings, in which—

Figure 1 is an inside face view of a collar embodying my improvements, in an open position, and having a tie secured therein.

Fig. 2 is an enlarged transverse sectional elevation taken on the line 2—2 of Fig. 1.

Fig. 3 is an enlarged fragmental, transverse sectional elevation taken on the line 3—3 of Fig. 1.

Fig. 4 is a view, in perspective, with a part broken away, of a collar having a tie secured in a manner peculiarly incidental to the arrangement and construction of the holding means on the collar.

Referring to the drawings by numerals 5 55 designates the collar top, that is the exposed

or outermost portion thereof, as worn, and 6 the collar band, that is the unexposed or innermost portion thereof, as worn.

The collar top 5 and its band 6 are both constructed of "soft" material and are to be 60 laundered and worn without starch, or other material which is not contributive or conducive to the wearer's comfort, and which is unsanitary and unwholesome, due to its tendency to "deposit" in the dermal pores of that 65 portion of the wearer's anatomy exposed to or engaging therewith.

The parts 5 and 6 are made of different lengths, and numbered as to size, as is common, and their weave or pattern of the textile, as well as their configurations, may be varied infinitely, as fashion may dictate, hence I in no sense wish to be understood as limiting myself to the configuration of the collar and band shown, which is illustrative 75 of a conventional design and serves only as a basis for the application and illustration of my improvements to collars of this type, generally.

As is common, the portion 6 is of greater 80 length than the portion 5, to provide extensions or tabs 7 and 8 in each of which there is a button-hole 9 and by preference the extension or tab 8 is of greater length than the tab 7, and its button-hole disposed nearer its 85 free end than the button-hole in the tab 8 so that when the collar is buttoned on the neck band of a shirt (not shown) the band will present a continuous, smooth surface between the spaced ends of the portion 5 or 90 collar top.

As clearly shown in Fig. 2, the collar top or portion 5 is constructed of a plurality of plies, as is the band or portion 6, and the margins of the portion 5 are inserted between the overturned margins of the plies of the portion 6, so that when the collar top is turned over the band, as when in use, or worn, the portion 5 will present a smooth, uninterrupted surface from its free margin 100 and over the "roll" or folding line.

The securing of the margins of the portion 5 between the margins of the plies of the portion 6 is preferably accomplished by a line of stitches 10 which extend for the 105 lengths of the two portions. However, prior to the securing of the two portions 5 and 6, as just recited, the one margin of each loop 11 and 12 is inserted between one of the plies of the portion 6 and the portion 5, so 110

that it may be held by the stitching 10. The loop 11 has at its margin opposite the one secured by the stitches 10, the line of stitches 13, which unite the plies of and finish the 5 one, or free, margin of the portion 6, and the loop 11 is disposed adjacent the end of the portion 6 but not in a position to cover the button-hole 9 at that end of the collar, while the loop 12 is secured in a like manner and position at the opposite end of the 10 collar.

From this showing it will be noted that the loops have widths equal to the width of the portion 6 or band of the collar, leaving a 15 relatively large free space or opening through which the tie 14 may be readily inserted and threaded.

Secured along one side margin of each loop 11 and 12 is a tape 15, which is free 20 throughout its length, except for its ends, and is relatively loose by reason of its entire length being greater than the spacing of its secured ends, and secured to the collar band adjacent the loops 11 and 12 is a button 16. 25 After the tie has been threaded through the two loops, the tapes 15 are secured on the buttons to serve as supports for the tie, for it is obvious that by reason of their overlying the tie and the tie resting on the buttons, the uppermost margin of the tie, will 30 be drawn and held to approximate registration with the folding line of the collar, as the tie is straightened as by pulling its ends.

By preference, the loops 11 and 12 are constructed of some relatively stiff material, 35 such as hair cloth so that they may additionally serve as stays to hold the collar upright, so that even though the collar at its folding line be temporarily distorted, as by 40 a downward or lateral movement of the head and chin, the stays will cause the collar to resume its normal shape upon a relaxation of the pressure of the chin.

Having thus described my invention, what 45 I claim and desire to secure by Letters Patent, is:—

1. A collar of the soft, turnover variety comprising the collar top and a band therefor, having means for attachment to a shirt, 50 a tie guiding and holding device secured adjacent each end of the collar band, a flexible

element at each of said devices and means for detachably securing the flexible element to the collar band.

2. In combination with a collar top and a 55 band therefor having means for attachment to a shirt, a loop arranged to receive therethrough a tie, a tape secured to said loop, and means for detachably securing the tape to the collar band. 60

3. In combination with a collar top and a band therefor, having means for attachment to a shirt, arranged to receive therebetween a tie, a loop constructed of relatively stiff material, through which the tie may be 65 threaded, a tape secured along one side of the loop and means for detachably securing the tape to the collar band whereby to hold the tie to its uppermost limit of movement in the loop and said stiff loop hold the collar top supported and smooth. 70

4. A collar having means for attachment to a shirt, an adjustable loop, secured to the collar adjacent said means of attachment and through which a tie may be threaded, 75 the adjustment of the loop providing for both facilitating the threading of a tie therethrough and a restriction of tie movements, for the purposes stated.

5. A collar of the turnover variety, having a loop of relatively stiff material, secured transversely of the collar band, adjacent each end thereof, the ends of said loops being secured at the margins of the band, whereby a tie threaded therethrough will be 80 held in proper relation with the collar and the collar top be held smooth and upright and means for securing the loops to the collar band intermediate their ends, which means constitute a support for a tie, substantially as set forth. 85

6. A collar of the turnover variety provided with a loop having its ends secured at the upper and lower margins of the collar band, and means for securing the loop to the collar 95 band intermediate said secured ends whereby a tie threaded through the loop, will be supported and held properly elevated and related to the upper margin of the collar, as set forth.

NATHAN J. GOODMAN.
